INSULATING DEVICE

Harold R. Owen, Venice, Calif., assignor to Electrical Products Corporation, Los Angeles, Calif., a corporation of California

Application March 29, 1941, Serial No. 385,891

8 Claims. (Cl. 173—339)

This invention relates to insulating devices and particularly to insulators of the kind to be mounted on plates of metal or other material and to electrically insulate elongated electrically chargeable bodies disposed either alongside the plates or extending through apertures in the plates. One field in which the invention is particularly useful is that of luminescent tube signs in which the tubes are mounted in spaced, parallel relationship to a plate which is the sign face and are mounted on the sign face by means of insulating supports secured to the sign face and extending outwardly therefrom.

It is one object of the invention to provide an insulating device, the parts of which may be secured to and assembled upon the plate by operative access to only one side of the plate.

It is another object of the invention to provide an insulating device of the character described which may be readily and speedily installed upon a plate without the use of attaching screws or rivets.

It is another object of the invention to provide an insulating device of the character described which shall be simple in construction and inexpensive to manufacture.

It is still another object of the invention to provide an insulating device of the character described by the use of which the luminescent tube may be spaced from the sign face plate at the minimum distance providing an air gap of adequate dielectric strength to prevent breakdown between tube and plate, and which shall have no metal parts disposed between the tube and plate which might contribute to a breakdown.

It is still another object of the invention to provide an insulating device of the character described by which a luminescent tube may be adjusted to vary the distance between it and the sign face plate.

It is yet another object of the invention to provide an insulating device of the character described by which, though the insulator is secured to the sign face plate, the position of the tube with respect to the sign face plate, in a direction transversely of the tube axis, may be varied within narrow limits to obviate the subjection of the tube to transverse stresses which might fracture it.

It is another object of this invention to provide an insulating device having two principal parts or members, one of which is a post of glass or other insulating material, and the other of which is a preferably metallic supporting device or holder for the post capable of ready installation in a perforation in a sign face plate in a se-

cure relationship to the plate such that it is not accidentally displaceable from the plate by gravity, by vibratory or other movement of the plate, or by other displacing forces.

5 It is another object of the invention to provide in an insulating device of the character described having such a post and post holder, such a structural relationship between the post and holder that when the two are installed in assembled position upon the sign face plate, the post may be securely held against accidental removal from the support and the support may in turn be securely held against accidental removal from the sign face plate.

15 The invention is adaptable for use in a number of different fields. In the following description and in the drawings, the invention is shown embodied in devices adapted for use on luminescent tube signs, but it is not therefore to be understood that the invention is confined to such embodiment.

20 In its broader aspects the invention is applicable to devices for mounting a body on a plate in spaced relationship thereto, particularly an elongated body in parallelism with a plate, and also particularly in a manner to provide adjustability of the spacing distance between the body and plate.

In the drawings which are for illustrative purposes only:

25 Fig. 1 is a utility view showing several different devices exemplifying several different forms of the invention respectively;

30 Fig. 2 is a sectional view of one of the devices shown in Fig. 1 taken along the line 2—2 of Fig. 1;

35 Fig. 3 is an elevational view of the insulating device shown in Fig. 2 taken in a plane at right angles to the sectional plane of Fig. 2;

40 Fig. 4 is a transverse sectional view taken along the line 4—4 of Fig. 2;

Fig. 5 is a longitudinal sectional view taken along the line 5—5 of Fig. 4;

45 Fig. 6 is an elevational view partly in section of a modified form of the insulating device of Figs. 2 to 5, which also embodies the invention.

Fig. 7 is a transverse sectional view taken along the line 7—7 of Fig. 6;

50 Figs. 8, 9 and 10 are elevational views of three other modified forms respectively of the insulating device of Figs. 2 to 5, which embody the invention;

Fig. 11 is a longitudinal sectional view of another of the insulating devices shown in Fig. 1, taken along the line 11—11 of Fig. 1;

55 Fig. 12 is a similar view of another of the in-

sulating devices of Fig. 1, taken along the line 12—12 of Fig. 1;

Fig. 13 is a longitudinal sectional view of yet another of the insulating devices shown in Fig. 1, taken along the line 13—13 of Fig. 1;

Fig. 14 is a longitudinal elevational view of another of the insulating devices shown in Fig. 1;

Fig. 15 is a perspective view of the insulator shown in Fig. 11.

Fig. 16 is a plan view of the sheet metal stamping from which is formed the holder used in the forms of the invention shown in Figs. 2 to 10, 12 and 13.

Fig. 1 shows a luminescent tube sign box assembly using several devices illustrative of several forms of embodiment of the invention. The assembly is shown in longitudinal section along a plane perpendicular to the front face of the sign. The sign box 10 comprises a front plate 11 which is the face of the sign, a rear wall 12, end walls 13, two side walls, only one of which, 14, appears in the figure, and partition walls 15.

Current of service voltage is led over conductors 16 into a transformer 17 where the voltage is converted to one suitable for use in luminescent tubes. Luminescent tubes 18 and 19 are supplied with current from the transformer 17 by conductors 20 and 21 and are electrically connected to each other by a conductor 22. The tubes 18 and 19 and conductors 20 and 21 are mounted upon, insulated from, and their positions determined with respect to the adjacent box walls by means of insulating devices 23, 24, 25, 26, and 27. Those insulating devices shown in Fig. 1 which are of the same construction are designated by the same numerals. Thus the two insulating devices 23 mounted in the partition walls 15 are of the same construction. The two insulating devices 25 are of the same construction which, however, is a construction different from that of the insulators 23. All of the insulating devices 23 to 27 inclusive are embodiments in various forms of the invention herein disclosed. The insulating devices designated by the numerals 23, 24, and 26, not only insulate a tube or conductor from an adjacent box wall, but also serve to support it thereon. The insulating devices 25, 27 insulate the tubes 18 and 19, respectively, from the sign face plate 11, but do not serve to secure the tubes in mounted position upon the face plate. They do determine the position of the tubes with reference to the plates, in the sense that, as will be later explained, they prevent lateral movement of the tube ends 28 and 29, respectively, to positions of contact with the edges of the apertures in the sign face plate 11 through which they pass.

The structural characteristics of the several insulating devices 23 to 27, inclusive, and the nature of their relationship to the luminescent tubes 18 and 19 and conductors 20 and 21 will appear from a detailed description of the several insulating devices.

Insulating devices 26 are shown in Figs. 2 to 5, inclusive. Each of the devices 26 comprises a post 30 of glass or other insulating material, a clip 31, and lashing wire 32.

The clip or holder 31 is preferably made from a metal stamping 33 (Fig. 16) of a general rectangular shape formed with a central portion or base 33a, flanges 34 on the sides of the base midway between the ends of the stamping, with notches 35 disposed centrally of each of its ends, and a central circular aperture 36 in the base 33a. Referring now to Figs. 2 to 5, each of the

end portions of the stamping 33 is bent back upon itself along a line adjacent the aperture 36 to form a narrow double-walled flange 37, is then bent to form a wall 38 at right angles to the central apertured portion of the stamping, and is finally bent radially outwardly to form a wall 39 parallel to the central portion of the stamping, and is finally bent away from the central apertured portion of the stamping to provide a radially outwardly bowed jaw 40. The jaw 40 is so shaped that its bifurcated tip 41 projects inwardly to points axially aligned well within the perimeter of the circle 36. The holder 31 by virtue of the aperture 36 and the separation of the jaws 40 is open along axial lines from end to end.

The clip 31 is installed in a rectangular aperture 42 in the sign face plate 11. The width of the clip, or, what is the same thing, the length of the walls 37, 38, and 39, and the distances 20 between the outside faces of the walls 38 are of such dimensions that the walls 38 snugly fit within the aperture 42 preventing the clip from transverse movement with respect to the peripheral edges of the aperture 42. The walls 38 provide 25 the holder with a grommet-like seat for a coaxial and non-rotative fit within the aperture 42 of the plate 11.

Axial movement of the clip with respect to the face plate 11 in a rightward direction, as shown 30 in Fig. 2, which will be herein referred to as an inward direction, is prevented by means of the double-walled flange 37 and the flanges 34. Axial movement of the clip in the opposite direction is prevented by the walls 38. It is obvious 35 that either the double-walled flange 37 or the flanges 34 but not both may be omitted from the construction of the clip in so far as preventing axial movement of the clip in an inward direction is concerned, and the wall 38 may be omitted 40 in so far as axial movement of the clip in an outward direction is concerned provided, in the latter case, that the jaws 40 are radially outwardly bowed as shown in the drawings.

The glass post 30 has a shank or stem 43 and 45 a head 44. The shank 43 is formed with suitable peripheral shoulders, for example, threads 45 extending from its inner end 46 a major portion of the distance to the head 44. The shank is further provided with an integrally annular flange or collar 47 disposed between the threads 45 and the head 44.

The head 44 is formed with a flat end face 48 lying in a plane perpendicular to the axis of the post and with a pair of diametrically oppositely 50 projecting lugs 49. Each of the lugs 49 is formed with an ear 50 extending inwardly parallel to the axis of the post and providing a recess 51. A luminescent tube 52 is lashed to the post in a position in which it is seated upon the end face 55 48 of the post by the flexible lashing wire 32. The wire is looped under the two lugs 49 passing through the recesses 51 and is double-stranded over the tubes 52 in the manner shown in Figs. 2 and 3.

60 In Figs. 2 and 3 the axis 53 of the tube is shown perpendicular to and lying exactly in the plane of the axis of the post. In the manufacture and assembly of the sign parts, it may result from deviations in dimensions that the tube axis 53 is transversely displaced with respect to the post axis and is nearer one or the other of the lugs 49. When such is the case the tube 52 may be lashed to the head 44 of the post in a transversely offset position, as shown in dotted lines in Fig. 2, 65 eliminating the application of a bending stress 70 75

to the tube which might result in its fracture. The flat character of the end face 48 makes it possible to thus offset the tube 52 on the head 44. If the head 44 were provided with a concavely recessed head such as is shown in Fig. 6, in accordance with the usual design of tube-supporting glass insulating posts, it is obvious that this transverse shifting of the tube with respect to the head to accommodate mis-alignment of the tube with the plate perforation 42 would be impossible of accomplishment.

In using the insulating mount shown in Figs. 2 to 5, the holder 31 is grasped between the thumb and fingers applied to the double-walled flange 37, and with the jaws 40 in advance is pushed through the plate aperture 42. In an obvious manner, the jaws 40 and with them the walls 38 and 39 are sprung inwardly by engagement of the jaws with the walls of the aperture 42 as they are forced through the plate and thereafter recoil outwardly causing the holder walls 38 to snugly fit within and engage the walls of the aperture 42 in a position in which the double-walled flange 37 prevents further inward movement of the holder and the walls 39 prevent outward movement of the holder through the plate 11.

The post 30 is then inserted through the opening 35 of the holder 31 with the post end 46 in advance, and pushed inwardly, the thread-engaging tips 41 riding over the crests of the threads 45 until the annular flange 47 engages the holder base 33a. As the post shank 43 passes between the tips 41 of the jaws 40, the jaws are spread apart and caused to apply a radially inwardly acting pressure to the shank 43, and to press the walls 38 more tightly against the walls of the aperture 42.

The post 30 is next rotated until the flange 47 is pulled tightly against the base 33a of the holder 31 as the tips 41 of the jaws 40 apply a resilient pressure to the outwardly directed side walls of the threads 45. The rectangular shapes of the base 33a and aperture 42 prevent rotation of the base in the aperture. The rotation of the post 30 is continued sufficiently to bend the jaws 40 without permanent deformation thereof and the rotation of the post is stopped with the end 44 disposed perpendicularly to the direction which the luminescent tube 52 will have after installation. It will be apparent that by turning the post 30 on its axis one or two times sufficient stress will be set up in the jaws 40 to securely clamp the post 30 against either longitudinal or transverse movement and will also bring about a tighter grip of the holder upon the plate 11.

The tube 52 is then lashed into position upon the end 44 of the post 30 by disposing it without flexing stresses against the end face 48 and lashing it thereto in the manner above described.

Figs. 6 and 7 show a modification of the insulating device 26. This modified insulating device is generally designated by the numeral 26j.

In the device 26j a collar 47j preferably made from an infrangible insulating material, such as hard rubber, is substituted for the collar 47 of the device 26. This collar is internally threaded for engagement with threads 45j of a glass post 30j.

In using the device 26j, the collar 47j is threaded upon the post 30j and placed in a position adjacent the head 44j of the post. The post is then thrust inwardly through the wall 11j to approximately the position required for proper spacing of tube 52j from the plate 11j and thereafter the

collar 47j is screwed inwardly upon the post to the point where it engages the outer surface of the plate 11j. Rotation of the collar 47j is continued sufficiently to bend jaws 31j without permanent deformation thereof. The rotation of the post is stopped with the end 44j disposed perpendicularly to the direction which the luminescent tube 52j will have after installation.

Fig. 8 shows an insulating mount in which is used a post 30a having a head 44a of the usual design. It is formed with an axially inwardly concaved end face 48a and lugs 49a to provide a cradle of a conformation to receive a glass tube 52a, which is lashed to the post 30a by means of lashing wire 32a in a manner similar to that described in connection with the form of the invention shown in Figs. 2 to 5 inclusive.

Since with this construction of head the tube is held rigidly against transverse displacement with respect to the head, it becomes necessary to otherwise compensate for any misalignment of the tube axis 53a with the axis of the rectangular aperture 42a in the plate 11a. This is accomplished by forming the circular aperture 36a of the holder 31a with a diameter such as to provide a substantial clearance between the walls of the aperture 36a and the crests of the threads 45a of the shank 43a of the post 30a, and by omitting the feature of an annular flange on the post such as flange 47 of the form of the invention shown in Figs. 2 to 5 inclusive.

When the post shown in Fig. 8 is pushed into position in the plate 11a, it is thereafter rotated in either direction, the engagement of the tips 41a with the threads 45a serving to regulate to a nicely the distance between the cradle 48a and the plate 11a and to permit disposition of the head 44a transversely of the axis of the tube 52a.

The clearance between the shank 43a and the aperture 36a provides the head 44a with a freedom to swing transversely to the axis of the tube 52a within a limited arc about the point of engagement of the tips 41a and the threads 45a to allow the tube 52a to assume positions of slight displacement with respect to the plate aperture 42a to compensate for any misalignment of the tube with the aperture 42a. In an insulating mount thus constructed, it is obvious that inward screwing of the post 30a will not tighten the grip of the tongue 40a upon the shank 43a nor will it tighten the grip of the holder 31a upon the wall of the aperture 42a of the plate 11a.

The threads of the post 30 or 30a may be so designed as to their crests and as to the slope of their side walls that either of these posts may be moved inwardly or outwardly without rotation by application of a pulling or pushing translative force of sufficient strength. It is desirable to be able to translatively push the post readily into approximately its ultimate position of assembly, but in some installations it may be also desirable to prevent removal of the post by a translative pull. This may be accomplished by forming the threads of the post of the buttress type, as

shown in Fig. 9, with the outwardly facing walls 54 of threads 45b of post 30b arranged either perpendicular to the axis of the post or at such a slight inclination thereto that the thread engaging tips of the holder tongue will not ride over the threads when the post is pulled outwardly.

Fig. 10 shows a modification of the invention in which a post 30c is formed with annular ridges 45c on its shank 43c. Crowns 55 of these ridges are rounded and depressions 56 between the ridges are preferably also rounded. The tips 41c of

the tongues 48c of the holder 31c are bent radially outwardly at their extremities to insure that these tips shall readily and smoothly ride over the crowns 55 when the post 30c is either pushed inwardly or pulled outwardly through the plate 11c, and shall at the same time engage the post 38c to prevent longitudinal movement thereof in the absence of the application of a pulling or pushing force of substantial strength.

In this form of the invention, the head 44c is placed in proper position transversely of the axis of the tube 52c by rotating the post. This rotation does not, of course, cause a longitudinal movement thereof with respect to the plate 11b. This form of the invention is in reality a modification of the form shown in Fig. 8 in that it is more particularly adapted for use with a post which is not provided with a collar such as that designated by the numeral 47 in the form of the invention shown in Figs. 2 to 5, inclusive. Such a collar is useless except in combination with spirally disposed threads on the shank of the post and due to the fluted character of the post shown in Fig. 10, it becomes impracticable to design the apertured holder base to restrain the post against transverse play within the aperture 36c, without the use of a clamping collar.

Fig. 11 shows the insulating device 27 of Fig. 1. In this device the post takes the form of an insulating cylinder or bushing 30d. The cylinder is provided preferably, although not necessarily, at its outer end with a flange 44d. Its inner end is threaded as shown at 45d and is formed with a flange 47d at the outer end of the threads 45d. The threaded portion of the post is inserted through an opening 42d of a plate 11d and is secured in position in the plate 11d by a holder 31d which is in all respects similar from a functional standpoint to the holder 31 shown in Figs. 2 to 5 inclusive, but is constructed from a length of spring wire bent to provide an annular ring 33d seated between the flange 47d and the plate 11d, and to further provide tongues 49d and thread-engaging tips 41d on the tongues 40d.

The cylinder 30d does not directly engage nor is it directly secured to a tube 52d. The tube 52d is disposed coaxially within the cylinder 30d which prevents contact between the tube 52d and the walls of the aperture 42d and interposes an insulating wall therebetween, thereby determining the position of the tube 52d with respect to the plate 11d.

Fig. 14 shows the insulating device 25 of Fig. 1. The holder 31e of this device is of identical construction with the holder 31d shown in Fig. 11. The post 30e takes the form of a receptacle having a closed end 57 on which is supported a conductor terminal 58 adapted for connection to a conductor cable outside of the receptacle and to the electrode of the luminescent tube 52e inside of the receptacle.

Apertures 42d and 42e, shown in Figs. 11, 14, and 15, are circular instead of having the shape of rectangles as do apertures 42, 42a, and 42c of the forms of the invention shown in Figs. 2 to 10, 12 and 13 but are notched at 59, to receive axially disposed sections 33d of the length of wire from which the holder 31d or 31e is formed. These wire sections 33d engage the walls of the notches 59. This engagement prevents rotation of the holder 31d or 31e when the post or bushing 30d or 30e is rotated to screw the bushing into position with respect to the plate 11d, and also prevents transverse displacement of the holder 31d or 31e in the aperture 42d or 42e.

The wire sections 33d in these respects correspond to the walls 38 of the holder 23, functioning as seats for the holder.

Fig. 12 shows an insulating device 24 of Fig. 1. It is similar to the insulating device 26 shown in Figs. 2 to 5, inclusive, with the exception of the head 44f which takes the form of an insulating cylinder with its axis perpendicular to the axis of the post 30f. The head 44f is adapted to support a conductor 61 and insulate it from the plate 11f which is a wall of a bracket 62 secured to the plate 11 in the manner shown in Fig. 1.

Fig. 13 shows an insulating device 23 having a holder 31g similar to the holders 31, 31a, 31c, and 31f, but the posts of which take the form of a cylindrical bushing similar to that shown in Fig. 11. This device is adapted for supporting flexible conductors, such as a conductor 63, on plates such as 15, through which they may pass and insulating them therefrom.

All of the insulating devices 23 to 27 inclusive are capable of determining the position of an electrically chargeable body with respect to a plate. Devices 23, 24, 25, and 27 limit transverse movement of the elongated electrically charged body and permit longitudinal movement thereof with respect to the device. These four devices when placed in a horizontal position are also capable of acting as supports for the elongated electrically chargeable body. When thus disposed horizontally in a vertical plate, they form insulating mounts for the elongated electrically chargeable body.

The insulating device 28 is adapted for determining the position of the elongated electrically chargeable body with respect to the plate in a definite fixed relationship to the plate.

The devices 28a and 28c determine the position of the elongated electrically chargeable body at a fixed distance from the plate and in parallelism therewith but permit a very limited variation in the relative positions of the body and the plate in directions parallel to the plate and transverse to the axis of the body. They also are insulating mounts.

All of the forms of the invention shown and described herein are adapted for assembly on an aperture plate by operative access to but one side of the plate. This characteristic is of special value in the assembly and installation of luminescent tube signs. Both for structural strength and to provide a housing for the transformer and current distributing conductor, the frame of such a sign is usually in the form of an enclosed box, the several walls of which are permanently secured together by welding or other suitable means. While the side walls, as, for instance, the side wall 14 shown in Fig. 1, are provided with manual access apertures (not shown), even with the help of the apertures, it is desirable in order to enable the operator to install such insulating devices as those designated 23 and 24 in Fig. 1, that these insulating devices be adapted for assembly and installation from one side only of the plates on which they are mounted. Devices 25, 26, and 27 may, by virtue of this characteristic, be installed in the face plate 11 by an operator working entirely from the outside of the box 13.

Devices 26, 26a and 28c illustrate how the invention makes it possible to mount the luminescent tubes or other elongated electrically chargeable body in close proximity to the plate 11. It is of advantage in many signs that the luminescent tube be mounted as close as pos-

sible to the sign face plate. If the luminescent tube is spaced a very substantial distance from the plate, and the sign is viewed from an angle to the plate, the reflected light from the tube against the plate and thence to the eye of the observer has the effect of producing a second visible character outline parallel to that visible to the observer by direct light radiation from the tube. While such a double-lined effect upon the eye of the observer is sometimes of advantage, in other cases it is a definite disadvantage. It is apparent that the closer the luminescent tube is disposed to the sign face plate, the less pronounced is this double lining and blurring of the sign character.

The metallic holder of this invention projects but very slightly from the sign face plate toward the luminescent tube. Since the post 30 is made of insulating material, it is apparent that this absence of any substantial projection of the holder 31 toward the tube enables the use of a post so short that the nearest point on the lashing wire 32 to the plate 11 may be the minimum distance for preventing electrical breakdown of the air gap between the lashing wire 32 and the plate. This distance is specified by the Underwriters Association as $\frac{1}{4}$ ". It will be also observed that in those forms of the invention in which an insulating collar is employed such as that shown in Fig. 2 designated by the numeral 47, the dielectric resistance to an electric discharge between the wire 32 and the plate 11 through the air adjacent the post surfaces is increased.

While in the drawings and description the invention has been shown in several concrete embodiments, it is to be understood that these several embodiments do not exhaust the possibilities of giving form to the principles of the invention. The scope of the invention is defined in the appended claims.

I claim as my invention:

1. In an insulating mount for determining the position of an elongated, electrically chargeable body with respect to an apertured plate and adapted for assembly on the plate by operative access to an outside only of said plate, the combination of: an axially open holder having a seat for coaxial fit within said aperture; means on said holder to engage said plate to retain said holder from axial movement inwardly of said aperture; radially inwardly yieldable means on said holder to engage said plate to normally retain said holder from axial movement outwardly of said aperture; an insulating member having a shank of a size for coaxial disposition within said holder, with an appreciable clearance between said shank and said holder at said seat; means on the outer end of said member for rigidly mounting said elongated, electrically chargeable body on said member in parallelism with said plate; and means on said holder disposed axially inside of said seat for engaging said shank in a manner to transversely fix said shank with respect to said holder at the point of engagement and inhibit outward movement of said shank with respect to said holder, said shank being unrestrained by said holder from angular movement within the limits of said clearance about said shank engaging means.

2. In an insulating mount for determining the position of an elongated, electrically chargeable body with respect to an apertured plate and adapted for assembly on the plate by operative

access to an outside only of said plate, the combination of: an axially open holder having a seat for a coaxial fit within said plate aperture; flanges on said holder at the outer end of said seat for preventing axial movement of said holder inwardly of said aperture; radially inwardly springable flanges on said holder at the inner end of said seat to contact the inner face of said plate for normally preventing axial movement of said holder outwardly of said aperture; a circumferentially ridged insulating post of a size to loosely fit within said holder at said seat; a cradle for a luminescent tube and means for lashing said luminescent tube fixedly in said cradle on the outer end of said post in parallelism with said plate; and at least two oppositely disposed, radially outwardly springable jaws on said holder projecting axially inwardly from said seat and each free to be sprung independently of any other jaw about its connection with said seat as a center so as to have its free end move in a direction substantially normal to the axis of said post, and each formed to normally yieldably press radially inwardly on said ridged post with its terminal tip in engagement with the side walls of said ridges.

3. In an insulating mount for determining the position of an elongated, electrically chargeable body with respect to an apertured plate and adapted for assembly on the plate by operative access to an outside only of said plate, the combination of: an axially open holder having a seat adapted to coaxially and non-rotatively fit within said plate aperture; flanges on said holder at the outer end of said seat for preventing axial movement of said holder inwardly of said aperture; radially inwardly springable flanges on said holder at the inner end of said seat for normally preventing axial movement of said holder outwardly of said aperture; an externally threaded insulating post sized to loosely fit within said holder at said seat; means on the outer end of said post for rigidly mounting said elongated, electrically chargeable body on said outer end in parallelism with said plate; and at least two oppositely disposed, radially outwardly springable jaws on said holder projecting axially inwardly from said seat and each free to be sprung independently of any other jaw about its connection with said seat as a center so as to have its free end move in a direction substantially normal to the axis of said post, and each terminating in a radially inwardly and axially inwardly directed tip formed to normally yieldably press radially inwardly on said threaded post in engagement with the side walls of said threads.

4. The combination defined in claim 3 in which the side walls of said threads are disposed at such an angle with respect to the axis of the post that said tips will ride over said threads when a force is applied axially to said post in either direction.

5. In an insulating device for determining the position of an elongated, electrically chargeable body with respect to an apertured plate and adapted for assembly on the plate by operative access to an outside only of said plate, the combination of: an axially open holder having a seat adapted to coaxially fit within said plate aperture; flanges on said holder at the outer end of said seat for normally preventing axial movement of said holder inwardly of said aperture; radially inwardly springable flanges on said holder at the inner end of said seat for normally

preventing axial movement of said holder outwardly of said aperture; an insulating member having a shank of a size for coaxial disposition within said holder; means on said member for determining the position of said elongated, electrically charged body with respect to said plate; and at least two oppositely disposed, radially outwardly springable jaws on said holder projecting axially inwardly from said seat and each free to be sprung independently of any other jaw about its connection with said seat as a center so as to have its free end move in a direction substantially normal to the axis of said post, and each formed to normally yieldably press radially inwardly on said shank and inhibit outward movement of said shank with respect to said holder, said jaws being rigidly connected extensions of said inwardly springable flanges and adapted when sprung radially outwardly to apply a radially outward force to said flanges.

6. In an insulating device for determining the position of an elongated, electrically chargeable body with respect to an apertured plate and adapted for assembly on the plate by operative access to an outside only of said plate, the combination of: an axially open holder having a seat adapted to non-rotatively fit within said plate aperture; flanges on said holder at the outer end of said seat for preventing axial movement of said holder inwardly of said aperture; radially inwardly springable flanges on said holder at the inner end of said seat for preventing axial movement of said holder outwardly of said aperture; a threaded insulating post sized to fit within said holder; means on said post for determining the position of said elongated, electrically chargeable body with respect to said plate; at least two oppositely disposed, radially springable jaws on said holder projecting axially inwardly from said seat and formed to yieldably press radially inwardly on said threaded post with their terminal tips in engagement with the outwardly directed side walls of said threads, said outwardly directed side walls being disposed at an angle to lock said post against outward movement with respect to said plate; and a radial projection axially fixed on said post adapted to press toward the outer face of said plate in the course of an inward movement of said post with respect to said plate.

7. In an insulating device for determining the position of an elongated electrically chargeable body with respect to an apertured plate and

adapted for assembly on the plate by operative access to an outside only of said plate, the combination of: an axially open holder having a seat adapted to non-rotatively fit within said plate aperture; flanges on said holder at the outer end of said seat for preventing axial movement of said holder inwardly of said aperture; radially inwardly springable flanges on said holder at the inner end of said seat for preventing axial movement of said holder outwardly of said aperture; a threaded insulating post sized to fit within said holder; means on said post for determining the position of said elongated, electrically chargeable body with respect to said plate; at least two oppositely disposed, radially springable jaws on said holder projecting axially inwardly from said seat and formed to yieldably press radially inwardly on said threaded post with their terminal tips in engagement with the outwardly directed side walls of said threads, said outwardly directed side walls being disposed at an angle to lock said post against outward movement with respect to said plate; and a collar threadedly mounted on said post and adapted to press toward the outer face of said plate.

8. In an insulating mount for determining the position of an elongated, electrically chargeable body with respect to an apertured plate and adapted for assembly on the plate by operative access to an outside only of said plate, the combination of: an axially open holder having a seat adapted to non-rotatively fit within said plate aperture; flanges on said holder at the outer end of said seat for preventing axial movement of said holder inwardly of said aperture; radially inwardly springable flanges on said holder at the inner end of said seat for preventing axial movement of said holder outwardly of said aperture; a threaded insulating post sized to fit within said holder; a head on the outer end of said post having a flat end face in a plane parallel to said plate; means for lashing a frangible tube against said end face of said post; axially resilient means on said holder projecting inwardly from said seat for clamping transversely and threadedly engaging said threaded post; and a radial projection axially fixed on said post adapted to move toward the outer face of said plate in the course of an inward movement of said plate through said aperture.

HAROLD R. OWEN.
